UNITED STATES PATENT OFFICE.

WILLIAM W. ALEXANDER, OF KANSAS CITY, MISSOURI, AND MANCEILLIA C. GILLHAM, OF KANSAS CITY, KANSAS.

MECHANICAL TELEGRAPH-SOUNDER.

SPECIFICATION forming part of Letters Patent No. 572,945, dated December 15, 1896.

Application filed April 23, 1894. Renewed May 18, 1896. Serial No. 592,072. (No model.)

To all whom it may concern:

Be it known that we, WILLIAM W. ALEXANDER, residing at Kansas City, in the county of Jackson, State of Missouri, and MANCEILLIA C. GILLHAM, residing at Kansas City, in the county of Wyandotte, State of Kansas, citizens of the United States, have invented certain new and useful Improvements in Mechanical Telegraph-Sounders, of which the following is a specification, reference being had therein to the accompanying drawings.

Our invention relates to a mechanical apparatus whereby signals transmitted by the electric telegraph may be accurately received and sounded without any local battery. As is well known, signals transmitted by the electric telegraph are received by means of an electric sounding device operated by the electrical energy supplied by a local battery. The efficiency of the electric sounding device is generally dependent upon the energy supplied by the local battery and the perfect condition of the electrical contact-points, as well as perfect adjustment of the telegraph-relay. If the line-current becomes impaired by partial ground, leaks, or low condition of line-battery, or the line adjustments are bad or the contacts are oxidized, the signals transmitted, if received, are sounded imperfectly, and therefore not understood. The local battery is troublesome, unreliable, and expensive, and the sounder being constantly affected by the variableness of the energy of both line and local batteries and having more or less magnetic lag frequently fails to sound the transmitted signals accurately.

It is the purpose of our invention to provide a simple mechanical apparatus of peculiar construction having a uniform source of mechanical energy for operating a telegraph signaling instrument according to and in unison with the electric signals transmitted by means of accurately-responding mechanism so organized that every vibration of the armature of the relay-magnet will be accurately sounded and with uniform energy and distinctness. These purposes we accomplish by the means illustrated in the accompanying drawings and hereinafter fully described, the same being definitely pointed out in the claims following the specification.

In said drawings, Figure 1 is a side elevation of a telegraph-sounder constructed in accordance with our invention, one of the sides of the inclosing frame being removed and the other sides shown in section. Fig. 2 is a transverse vertical section of the same. Fig. 2^a is a longitudinal section of the hair-spring shaft and its supports.

In said drawings the supporting-base for the mechanism is shown at B and rests upon and is secured to a base-board B², upon which are also mounted the relay-magnet M and the pivot-bearing A² of the armature A. The upper end of said armature is united by means of a connecting-rod R with the lower end of a substantially vertical lever R², that is pivotally mounted upon a horizontal shaft r², having its ends journaled in vertical plates C, one of which may form one of the sides of the frame C² that incloses the mechanism. The lever R² is allowed to oscillate with its pivot-shaft r², but to regulate the angle of its oscillation its upper end is located between two adjustable stops L and L², that are in the form of screws having their points toward said lever, said screws being received in lugs pendent from the top of the frame C², but said lugs may project from other parts of the frame.

The pivot-shaft r² of the lever R² is provided with arms S and S², rigidly attached thereto radially, but divergent from each other, as escapement-pallets, and the outer ends of said arms are bent in the form of hooks to adapt them to act as detents. To the side of the lever R² opposite that occupied by the rod R is attached one end of a retractile spring R³, that has its opposite end connected to the upper end of a pivotally-mounted lever R⁴. Said lever is pivoted at r⁴ to a bearing projecting inwardly from the frame C² and has its lower end bearing against the point of an adjusting-screw R⁵.

D represents a gear-wheel rigidly secured upon a shaft d, to which is attached a crank-handle d², by which it may be revolved in the direction shown by the arrow on the wheel D, a spring-pawl D² being shown in engagement with the teeth of said wheel; but it must be understood that said wheel D can be rotated by any well-known means, such

as a power-train, or by belts or sprocket-chains passing around pulleys mounted upon its shaft and suitable devices rotated by compressed air, steam, or other power.

5 The gear-wheel D meshes with a pinion P, loosely mounted upon a stud p, secured to the frame C². Said pinion has rigidly fastened to its inner face an arm P², the free end of which is bent parallel with the stud p and has adjustably secured thereto the outer end of a hair-spring H. The inner end of said spring is secured to a collar rigidly attached to a shaft H², and said shaft has one end tubular and mounted upon the end of the stud p, while the opposite end of the shaft is supported by a hanger H³, secured to the under side of the sounder Q.

Rigidly fastened to the shaft H² are two detaining-arms h and h², arranged diametrically, but the outer end of the arm h² is bent slightly to one side, so as to engage alternately with the two pallets 2 and 4 of a stop-pinion M, the arm h being adapted to engage with the other two pallets 1 and 3 of said stop-pinion. Said pallets 1 and 3 are in a plane in the path of the arm h, while the pallets 2 and 4 are in the path of the bent end of the arm h², and consequently in a plane alongside of the plane of the pallets 1 and 3. The stop-pinion m is mounted upon and attached to a shaft m², and upon said shaft are also diametrically mounted two arms n and n², which are in the same plane with the oscillating arms S and S² of the shaft r² and alternately come in engagement with said oscillating arms. Upon the inner end of the shaft H² is attached a crank h³, having pivoted thereto a connecting-rod t in a substantially vertical position. To the upper end of said rod t is pivotally attached one end of a spring t², having its opposite end rigidly secured to the lower end of a rod t³, and the latter rod has its upper end rigidly attached to the sounder-lever T. Said lever has one end pivoted at q to a standard mounted upon the sounder Q, while its opposite end is adapted to vibrate vertically between the arms of an angular frame Q², secured upon the sounder. The upper arm of said frame carries an adjustable stop q² above the free end of the sounder-lever T, and said lever also carries an adjustable stop q³, adapted to rest upon the lower arm of the frame Q².

The object of the spring t² on the lower end of the rod t³ below the sounder-lever is to cushion the blow imparted to said sounder-lever and to permit the movement of said lever without releasing the energy of the hair-spring H, and thus prevent shocks to the mechanism.

The operation of the apparatus is as follows, viz: In Fig. 1 the relay-armature is shown as attracted by the magnet M against the tension of the retractile spring R³. Now if the magnet M is discharged the spring R³ will pull the pivotally-mounted rod R² until its upper end rests against the limiting-stop

L, thus allowing the arm S² and the arm n² to be disengaged by the propelling energy of the spring H and the arm n to move in engagement with the arm S. The stop-pinion m making a one-quarter revolution, the arm h moves from engagement with the pallet 1 of the stop-pinion m and the arm h² moves into engagement with the pallet 2 of said stop-pinion m, thereby allowing the shaft H² and the crank h³ to make a one-half revolution, pressing the sounder-lever T against the upper stop q² of the sounder Q by means of the uplifting of the connecting-rod t, spring t², and rod t³. This operation completes the mechanical movement of the parts impelled by the energy of the spring H upon the discharge of the magnet M. Now if the magnet M again attracts the armature A against the tension of the retractile spring R³ the armature A, by means of the rod R, pulls the pivotally-mounted rod R² until the upper end thereof rests against the limiting-stop L², as shown in Fig. 1, thereby allowing the arm n to leave the arm S and to engage with arm S², completing a one-quarter revolution of the stop-pinion m, the arm h² moving from engagement with the pallet 2 of the stop-pinion m and causing the arm h to engage with the pallet 3 of said stop-pinion m, thus permitting the energy of the spring H to revolve the shaft H² and the crank h³ a one-half revolution with a downward pull on the connecting-rod t, spring t², and rod t³, forcing the sounder-lever T down upon its bottom stop q³, the latter resting on the frame Q² of the sounder Q, completing the mechanical movement of the parts when the magnet M is attracting the armature A. When the magnet M again discharges, the retractile spring R³ pulls the pivotally-mounted rod R² and its connected parts until the upper end thereof rests against the limiting-stop L, allowing the arm S² and the arm n² to be disengaged by the propelling energy of the spring H and the arm n² to move to engagement with the arm S, the stop-pinion m making a one-quarter revolution. The arm n is disengaged from the pallet 3 of the said stop-pinion m and the arm n² moves to engagement with the pallet 4 of said stop-pinion m, thereby allowing the shaft H² and the crank h³ to complete a one-half revolution, pressing the sounder-lever T against the stop q² of the sounder by means of the uplifting of the connecting-rod t, spring t², and rod t³. This operation completes the mechanical movement of the parts impelled by the energy of the spring H upon the second discharge of the magnet M.

When the magnet M again attracts the armature A, said armature, by means of the rod R, pulls the pivotally-mounted rod R² against the tension of the retractile spring R³ until the upper end of the rod R² rests against the limiting-stop L², allowing the arm n to leave the arm S and to engage with the arm S². The stop-pinion m, making a one-quarter revolution, releases the arm h² from engagement

with the pallet 4 of said stop-pinion m and allows the arm h to engage with the pallet 1 of said stop-pinion m , as shown in Fig. 1, and thereby allowing the energy of the spring 5 H to revolve the shaft H^2 and crank h^3 a one-half revolution with a downward pull on the connecting-rod t , spring t^2 , and rod t^3 and forcing the sounder-lever T down with the bottom stop q^3 upon the sounder. This operation completes the mechanical movement of the parts impelled by the energy of the spring 10 H upon the magnet M attracting the armature A and completing the four phases of the one revolution of the stop-pinion m .

15 We do not restrict ourselves to four pallets on the stop-pinion m , as the mechanical principle involved will admit of any number of pallets being used.

Having now fully described our invention, 20 we claim—

1. A mechanical telegraph signaling instrument consisting of an electromagnet, its armature, an oscillating lever R^2 connected therewith, a retractile spring R^3 attached to 25 said lever, adjustable stops on opposite side of said lever, a pivot-shaft for said lever, hooked arms S and S^2 secured to said shaft and a pivoted arm n^2 to engage with said arms S and S^2 , pallets and a crank upon the pivot-shaft m^2 of the arm n^2 , a springy connecting-rod uniting said crank with a pivoted sounder-lever, pivoted arms h h^2 to engage alternately 30 with the pallets on the shaft m^2 , a coiled spring mounted upon the pivot-shaft of the arms h h^2 and having one end connected to a pinion 35 P , with means to rotate said pinion substantially as described.

2. In a telegraph signaling instrument the combination of an electromagnet, its armature, an oscillating escapement connected therewith, rotary arms n n^2 engaging with said escapement-pallets upon their shaft, arms h h^2 for engagement with said pallets, a shaft carrying a coiled hair-spring and a crank, a springy connecting-rod uniting said crank to 45 a sounding-lever, a pinion connected with the hair-spring and means to rotate said pinion substantially as described.

3. In a telegraph signaling instrument the combination of an electromagnet, its armature, an oscillating and a rotary escapement with a coiled hair-spring upon the shaft carrying the controlling-arms of the rotary escapement, a crank upon said shaft, a sounding-lever, a connecting-rod uniting said crank 50 with the sounding-lever, a pinion connected with the hair-spring and means to rotate said pinion substantially as described.

4. In a telegraph signaling instrument the combination of an electromagnet, its armature, an escapement connected with said armature, a sounding-lever, a springy connecting-rod uniting said sounding-lever with a crank upon a shaft carrying a coiled hair-spring, a pinion connected with said hair-spring and means to rotate said pinion 55 substantially as described.

In testimony whereof we affix our signatures in presence of two witnesses.
